NOISELESS TYPEWRITER

Camillo Olivetti, Ivrea, Italy

Application October 3, 1935, Serial No. 43,438
In Italy October 27, 1934

9 Claims. (Cl. 197—22)

It is well known that one of the greatest difficulties usually met in the construction of noiseless typewriters lies in the necessity of giving a marked rigidity to the movable parts which actuate the type levers, in order not to lose in the elastic deformation of these parts a considerable amount of the power available for the writing operation, thus lowering the efficiency of the typewriter.

10 My invention involves a new principle, whereby, at the moment of printing, the paper carrying platen is advanced and pressed against the type. The platen is advanced to the position in which a print is made by means of a kinematic mechanism so designed that, when the key on the keyboard is pressed, the speed of the type lever will be gradually reduced to zero and the type will be held firmly against the moving platen until the print is accomplished.

20 The operation and the advantages of a typewriter embodying my invention will be better understood by considering the following:

If the paper carrying platen were extremely light, it would be necessary to impart to it a very high speed in order to obtain a kinetic energy of sufficient magnitude to equalize the printing work. This manner of operating would be substantially the same as takes place in the prior art typewriters, though obtained by a wholly different mechanism. If, on the contrary, the paper carrying platen were very heavy, a low speed would be sufficient to obtain the same kinetic energy, but in such a case the type bar should possess a high rigidity. Thence the typewriter would present the same difficulties of construction as the prior art models.

However, it is easily understood that through a proper choice of the weight of the paper carrying platen a sufficient kinetic energy can be imparted to it even with a low speed or a short motion, and that the approaching speed of the platen can be held within so small a limit that the noise resulting from the stroke will be extremely reduced.

45 A further advantage of the present invention will be found considering that, as will be better explained, it is possible to regulate within ample limits the time during which the paper is pressed against the type; moreover, this fraction of time will be longer than in the prior art models, without in the least lowering the typing speed. Also, the print is substantially improved, as it is well known that the longer the pressure the greater 50 the quantity of ink transferred from the ribbon

(placed as usual between the type and the paper) to the paper.

5 While the following specifications and the accompanying drawings show an embodiment of the present invention, it is apparent that any other device which will perform on the above-mentioned principle may be regarded as suitable.

10 As will be better explained later, the paper carrying platen is actuated by means of a spring which is loaded, every time a print is made, by the so-called universal bar. Therefore, it is the pressure of the typist's finger on the key which causes the forward motion of the paper carrying platen; however, this motion can be obtained in many other ways.

15 The type bar mechanism may be varied too; as a matter of fact, any kind of connection will be suitable if capable of slowing down the motion of the type when the latter approaches the position in which a print is to be made and holding 20 the type firmly when the paper carrying platen is pressed against it.

25 In the accompanying drawings:

Figure 1 is a fragmentary sectional view showing the type bar mechanism in the position 25 of rest;

Fig. 2 is a similar view showing the type bar mechanism in the printing position;

Fig. 3 is a similar view showing the type bar mechanism in the position in which a print is 30 not yet made but the type bar is held standing while the platen is beginning its forward motion; and

Fig. 4 and 5 are detail views of the linkage used to determine the forward motion of the 35 platen.

With reference to Fig. 1, the key lever 1 is pivoted at 2 and, through lever 3 pivoted at 4, rocks lever 5 about its fulcrum 6. The end of lever 5 carries a stud 7 slidably positioned in a 40 slot 8 cut in the lever 9 pivoted at 10. The slot 8 is so designed in correspondence with the operating lever 5 that the speed of lever 9, very slow at the beginning of its stroke, is evenly accelerated as the stud 7 approaches the bearing or 45 pivot 10 of the type lever 9, again reduced as the stud moves away from pivot 10 and finally stopped in the printing position when the longitudinal axis of the slot is tangent to the circle described by the stud 7. It will be noted that in 50 this position a further pressure on the key will only hold the type still, without effecting a backward movement of the type. Consequently, this structure will easily withstand the thrust from 55 the paper carrying platen.

The platen is fixed to the frame 12 of the carriage by means of a parallel linkage composed of two cranks 13 and 14 and a T-shaped connecting rod 15 which will restrict motion of the platen to a horizontal direction, perpendicular to the axis of the platen. A slot 37 is formed in the upper vertical portion of connecting rod 15 which provides a bearing for the shaft of the paper carrying platen 11 so that the latter can 5 assume a vertical motion, whereby each one of the types carried by the type lever can strike on the platen.

A bar linkage of this type is provided at both ends of the paper carrying platen and the two 10 connecting rods or bars 15 are coupled together by a rod 16 of the same length as the platen. This rod 16 is engaged by a forked lever 17 pivoted at 18 which serves to impart to the paper carrying platen a small transverse motion toward 15 and away from the type without interfering with the lateral shift of the whole carriage. A spring 19 urges lever 17 against a stop 20 and the platen 11 toward the position in which a print will be 20 made. The type levers 9 are cam-shaped in the 25 proximity of their bearing, so that they can operate the universal bar 21. As is well known, the universal bar actuates the escapement and the shifting of the inked ribbon, and furthermore, as 25 will be explained later, it effects a motion of lever 30 17 in such a way as to push back the paper carrying platen and load spring 19. When a predetermined position is reached the spring 19 is allowed to act, pushing forward the paper carrying 35 platen, which presses the paper against the type.

For this operation, any suitable mechanism can be used. In the mechanism shown in the drawings, lever 17 is controlled by a toggle linkage composed of two links 22 and 23. Link 22 is pivotally connected to the end of lever 17 and link 23 is pivoted on the frame at 24. Link 23 is fork-shaped at one end (see Figs. 4 and 5) and supports (in the proximity of, and perpendicularly to, shaft 24) a swinging lever 26 provided with 40 two lugs 27 and 28. Lever 26 is pivotally mounted on stud 25 so that lugs 27 and 28 may alternatively be shifted to register with two other lugs 29 and 30 provided on the moving plate 31. Cranks 32 and 33 are pivotally mounted at their 45 lower ends to the frame of the machine and carry at their upper ends the plate 31. Motion is imparted from the universal bar 21 to plate 31 by means of a rod 34 and a lever 35 pivoted at 36.

Fig. 4 represents a front view of the swinging lever 26 and shows a section of the lugs 29 and 30 of plate 31.

In the position of rest, as shown in Fig. 1, the links 22 and 23 are out of alignment and lug 27 50 on the swinging lever is opposite lug 29 of plate 31. When plate 31, actuated by the universal bar, advances, lug 29 engages lug 27 and compels link 23 and the swinging lever 26 to revolve around stud 24. The two links 22 and 23 are now in 55 the same line, as shown in Fig. 3, and they compel lever 17 to rotate in a clockwise direction around bearing 18, loading the spring 19 and shifting the paper carrying platen to a position away from the type.

Upon further motion of the universal bar and the consequent advance of plate 31, the toggle links 22 and 23 pass over their dead center position and lever 17 is permitted to rotate counter-clockwise under the action of spring 19, bringing 70 the whole system in the position shown in Fig. 2

and pushing the paper carrying platen against the type, as the type lever 9 has in the meantime reached its final position. An impression is made and spring 39, pulling on lever 5, causes it to rotate clockwise to return the type lever mechanism to its rest position, while spring 40 returns the universal bar and all the parts connected to it to their rest position.

On account of the sudden swinging of links 22 and 23, the lug 27 of swinging lever 26 is disengaged from lug 29 of plate 31 and lug 28 is shifted to a position alongside of lug 30 which it retains until plate 31 is returned to the rest position together with the universal bar.

At the next stroke, in order to obtain the same movement of the various parts it is necessary that lug 30 engage against lug 28 of swinging lever 26. Therefore, lever 26 must be shifted to move lug 28 into the path of travel of lug 30, while lug 27 must be moved to a position out of the path of travel of lug 29. This is effected by a small leaf spring 41 horizontally fixed on the typewriter frame at 42. Its free end is engaged between two studs 45 and 46 provided on arm 47 of the swinging lever 26; the latter, as already stated, is pivoted at 25 on the fork-shaped extremity of rod 23. The leaf spring is also engaged between two studs 43 and 44 provided on link 22. When the links 22 and 23, which compose the toggle linkage, are shifted upwards or downwards, the leaf spring is bent in the same direction and actuates, through studs 45 and 46, the swinging lever in such a way that lug 27 will be in the path of lug 28 when the linkage is shifted upwards, while lug 28 will be in the path of lug 30 when the linkage is shifted downwards.

When the toggle linkage, during the operation of the typewriter, suddenly alters its position, the elasticity of the spring 41 allows the lugs 27 or 28 of swinging lever 26 to slide laterally on plate 31, thus taking the right position with regard to the path of travel of plate 31 when the return stroke is nearly completed.

As already stated, the above-described mechanism is only one of the many mechanisms for carrying out the present invention.

The forward motion of the paper carrying platen is, in the described example, obtained through the links 22 and 23 by means of the thrust of spring 19 in such a way that the acceleration of said platen is positive. With other systems, this acceleration may be negative or even zero, i. e., the paper carrying platen will advance with a constant speed.

The different ways of effecting this mechanism are to be determined with reference to the weight of the platen, in correspondence with the various characteristics which it is desired that the typewriter possess. This may preferably be eminently dynamic (corresponding to a quick motion of the paper carrying platen) or eminently static (low motion of the platen, but high thrust between paper and type), in consequence of which the typewriter will be more or less noiseless with reference to other characteristics.

Anyway, it shall be understood that my invention is based on the simultaneous movement of a type bar mechanism which will bring the type into the printing position with a reduced motion and hold it firmly for a fraction of time while another mechanism, controlled by the universal bar which is pressed by the typist, serves to push forward the paper carrying platen to press it against the type.

Incidentally, it should be noted that the initial position of the paper carrying platen may be

slightly varied so the latter can meet the type a little before it has reached its final position, yet possessing a residual speed, or just when the type is standing still, or even when it has already begun its backward motion. In the latter case, the action of printing is effected through the differential speed of the type bar and the paper carrying platen.

I claim:—

1. In a typewriter of the character described, a plurality of type, means for advancing the type to a printing position, a platen shiftable toward and away from the printing position of the type, and means operable upon advancing the type from a position of rest to the printing position to shift the platen away from the printing position and then advance the same to the printing position to engage the type.

2. In a typewriter of the character described, a plurality of type, means for advancing the type to a printing position, a platen shiftable toward and away from the printing position of the type, and means including a toggle linkage operable upon advancing the type from a position of rest to the printing position to shift the platen away from the printing position and then advance the same to the printing position to engage the type.

3. In a typewriter of the character described, a plurality of type, means for advancing the type to a printing position, a platen shiftable toward and away from the printing position of the type, resilient means urging said platen to the printing position, and means operable upon advancing the type to the printing position for shifting the platen away from the printing position and allowing it to return under the action of the resilient means.

4. In a typewriter of the character described, a plurality of type, means for advancing the type to a printing position, a platen shiftable toward and away from the printing position of the type, resilient means urging said platen to the printing position, and means including a toggle linkage operable upon advancing the type to the printing position for shifting the platen away from the printing position and allowing it to return under the action of the resilient means.

5. In a typewriter of the character described, a plurality of type bars, means for advancing the type bars to a printing position, a platen shiftable towards and away from the type of the type bars when the latter are in printing position, resilient means urging said platen toward the printing position, a universal bar actuated by the type bars, and means actuated by said universal bar for shifting the platen away from the printing position during advance of the type bars to the printing position and allowing the same to return under the action of the resilient means when the type bars arrive at the printing position.

6. In a typewriter of the character described, a plurality of type bars, means for advancing the type bars to a printing position, a platen shiftable towards and away from the type of the type bars when the latter are in printing position, resilient means urging said platen toward the printing position, a universal bar actuated by the type bars, and means including a toggle linkage actuated by said universal bar for shifting the platen away from the printing position during advance of the type bars to the printing position and allowing the same to return under the action of the resili-

ent means when the type bars arrive at the printing position.

7. In a typewriter of the character described, a plurality of type bars, means for advancing the type bars to a printing position, a platen shiftable towards and away from the type of the type bars when the latter are in printing position, resilient means urging said platen toward the printing position, a universal bar actuated by the type bars, a toggle linkage comprising a pair of connected links, the first of which has its free end connected to the platen and the second of which has its free end mounted on a stationary pivot, and means actuated by said universal bar during advance of the type bars to a printing position for shifting said linkage from a position wherein the links are at an angle to each other through a position wherein the links are aligned, to move the platen away from the printing position, to a position wherein the links are again at an angle to each other to allow the resilient means to return the platen to the printing position.

8. In a typewriter of the character described, a plurality of type bars, means for advancing the type bars to a printing position, a platen shiftable towards and away from the type of the type bars when the latter are in printing position, resilient means urging said platen toward the printing position, a universal bar actuated by the type bars, a toggle linkage comprising a pair of connected links, the first of which has its free end connected to the platen and the second of which has its free end mounted on a stationary pivot, a rocker arm carried by said second link and shiftable in a plane perpendicular to the center line of the second link, lugs carried by the ends of said rocker arm, and means actuated by said universal bar for engaging one of said lugs to shift the linkage through its dead center to move the platen away from the printing position and allow it to return under the action of the resilient means.

9. In a typewriter of the character described, a plurality of type bars, means for advancing the type bars to a printing position, a platen shiftable towards and away from the type of the type bars when the latter are in printing position, resilient means urging said platen toward the printing position, a universal bar actuated by the type bars, a toggle linkage comprising a pair of connected links, the first of which has its free end connected to the platen and the second of which has its free end mounted on a stationary pivot, a rocker arm carried by said second link and shiftable in a plane perpendicular to the center line of the second link, lugs carried by the ends of said rocker arm, a member provided with a pair of lugs to engage the lugs on said rocker arm, means actuated by said universal bar for moving said member toward said rocker arm to shift the toggle linkage through its dead center and move the platen away from the printing position and allow it to return under the action of the resilient means, and means associated with said toggle linkage and operable upon passage of said linkage through its dead center for shifting said rocker arm to place the lug at one end in the path of travel of a lug on the member and to place the lug on the other end out of the path of travel of a lug on said member.

CAMILLO OLIVETTI.
